B. P. HALL,

APPARATUS FOR ATOMIZING LIQUIDS, SUCH AS PAINTS, INKS, VARNISHES, &c.

APPLICATION FILED JUNE 18, 1917.

1,261,122.

Patented Apr. 2, 1918.

FIG. 1.

Inventor
Burton P. Hall

By His Attorney
Israel Benjamin.

UNITED STATES PATENT OFFICE.

BURTON P. HALL, OF FANWOOD, NEW JERSEY.

APPARATUS FOR ATOMIZING LIQUIDS, SUCH AS PAINTS, INKS, VARNISHES, &c.

1,261,122.

Specification of Letters Patent.

Patented Apr. 2, 1918.

Application filed June 18, 1917. Serial No. 175,482.

To all whom it may concern:

Be it known that I, BURTON P. HALL, a citizen of the United States, residing at Fanwood, in the county of Union and State 5 of New Jersey, have invented a new and useful Apparatus for Atomizing Liquids, such as Paints, Inks, Varnishes, and Others, of which the following is a specification.

My invention relates to improvements in 10 an apparatus for atomizing liquids, in which a gas, such as air, is employed to induce a current of liquid, such as paint, and atomize the same, and it consists in the novel features, hereinafter more fully described.

15 The objects of my improvement are:

First: to produce an apparatus for atomizing liquids, wherein the requisite air under pressure is obtained preferably by manual or foot power.

20 Second: to permit the air compressing means of my apparatus to be kept comparatively stationary, while the atomizer is adapted to be moved freely to and from any object, thereby affording facility for 25 applying the jet of atomized liquid to said object.

Third: to provide an extensible connection from the air compressing means to the atomizer.

30 Fourth: to have the entire apparatus portable, simple, durable and inexpensive; and fifth, to improve the details of design in both the air compressor and the atomizer.

I attain these objects by the apparatus 35 illustrated in the accompanying drawings, in which—

Figure 1 is a side elevation of my apparatus, including the foot board of the air compressor; Fig. 2 is an end elevation of 40 the lower end of the air compressor.

Similar numerals refer to similar parts throughout the views of the drawings.

45 11 designates the cylinder of an air compressor, containing the piston 12; 13 is the piston rod and 14 the handle for manually operating the piston 12. To keep the cylinder 11 in the position shown in the drawings while working the piston 12, I provide the foot board 15—16, which is made in 50 two parts 15 and 16, collapsibly connected to each other by means of the hinges 17, and they may be kept in line by a suitable latch, which is not shown in the drawings.

The lower end of the cylinder 11 is shown 55 as connected at its lower end to a stirrup 18, which may be connected to the foot board

15 by suitable fastenings, not shown in the drawing.

The foot board 15—16 serves as a means for keeping the air pump vertical and stationary by means of the foot of the operator.

19 is a hose nipple connection from the lower end of the cylinder 11 to a flexible tube 20, which is provided for passing the compressed air from the cylinder 11 to the container 22 of the atomizer, to which said tube 20 is connected by means of the nipple 21.

The length of the tube 20 may be much greater than is shown in the drawings, thereby affording freedom of motion for said container 22, which is provided with a cap 31, which carries the suction tube 23, adapted to reach down almost to the bottom of the container 22.

25 The upper end of the suction tube 23 is open, and adapted to register with the lower end of one of a number of liquid discharge nozzles 30, carried by a revolving sector 26, which is pivotally connected to the bridge 27 by means of the post 25, which carries 30 the stationary nozzle 24, made in one with said nipple 21.

28 is the inner end of said post 25, which may be riveted to said cap 31; 29 is a vent passing through said cap 31 and adapted to 35 allow atmospheric air to replace the liquid discharged from the container 22.

The operation of my apparatus is as follows:

30 By stepping upon the foot board 15—16 90 the operator is enabled to work the piston 12 by means of the handle 14 at ease with one hand, while applying the jet of liquid from the nozzle 30 as atomized and directed by the jet of air from the nozzle 24.

45 The long flexible tube 20 permits the continuous moving of the container 22 into any convenient position for the work, which is at hand, without moving the larger and more cumbersome air pump.

50 The sector 26 is preferably made with a few nozzles 30, of different sizes, which are readily replaceable by revolving said sector 26, which is also adapted to act as a stopper for the upper end of said suction tube 23, 105 when none of the nozzles 30 is in registration with said suction tube 23.

55 Many changes could be made in my apparatus for atomizing liquids within the scope of my invention.

100 I do not therefore restrict myself to the details of design of my apparatus as shown;

but I intend to include also all mechanical equivalents and obvious modifications of the same.

What I claim as my invention, and desire 5 to secure by Letters Patent is:

In a portable apparatus for atomizing liquids the combination of a manual air compressor, an atomizer, a flexible tube, con-

necting said air compressor to said atomizer, and a collapsible foot board connected at 10 the lower end of said air compressor, said foot board being adapted to keep said air compressor substantially stationary by means of the foot of the operator.

BURTON P. HALL.
